UNITED STATES PATENT OFFICE

2,496,517

PORTABLE CLOTHES DRIER

John E. Bradley, Jr., Portland, Maine

Application June 4, 1948, Serial No. 31,067

1 Claim. (Cl. 219—39)

1
The present invention relates to portable clothes dryers and it consists in the combinations, constructions and arrangements of parts herein described and claimed.

It is an object of the present invention to provide a portable clothes dryer which will take up a minimum of space and which is light in weight.

Another object of the invention is the provision of an apparatus of the character set forth which may be used in conjunction with a standard home laundry machine.

Another object of the invention is the provision of a novel housing for a thermostat.

Another object of the invention is the provision of an apparatus of the character set forth, of novel means for converting steam and water vapor into water.

A further object of the invention is the provision of novel means and apparatus for the heating of air.

Other and further objects of the invention will become apparent from a reading of the following specification taken in conjunction with the drawings, in which:

Figure 1 is a side elevational view, partly in section, of an embodiment of the invention,

Figure 2 is an enlarged sectional view taken along line 2—2 of Figure 1,

Figure 3 is a sectional view taken along line 3—3 of Figure 2,

Figure 4 is an enlarged sectional view taken along line 4—4 of Figure 1,

Figure 5 is an enlarged sectional view taken along line 5—5 of Figure 2,

Figure 6 is a side elevational view of another form the invention may take,

Figure 7 is an enlarged vertical sectional view of the principal part of the apparatus shown in Figure 6, and

Figure 8 is a fragmentary sectional view illustrating certain details of construction.

Generally there is provided a light, compact and portable apparatus which may be equipped to interconnect with a washing machine of the standard home types now in use whereby the washing machine may be utilized in connection with the present apparatus as a drying machine. The present invention contemplates a horizontally extending cylindrical chamber having electrical heating coils therein and having a motor-operated blower either within one end of the cylindrical chamber or attached thereto as an individual unit. In the more compact form the device is provided with a pair of runners for the purpose of supporting it and the exhaust end of the ap-

paratus is connected by a hose to the soap door of a washing machine. In the other type shown and described herein a novel support and bracket is provided and the exhaust end of the apparatus is provided with a nozzle which fits in the drain case housing and is provided with a plug adapted to fit in the drain hole of the float chamber usually found in such machines. A thermostat is mounted in a housing which may be placed within the soap door of the washing machine and the thermostat is connected in the circuit supplying the heating coils.

Referring more particularly to the drawings, there is shown therein a washing machine 10 of standard manufacture having a conventional loading door 11, and a soap door 12 within which is a soap funnel 13 leading to the washing machine compartment 14. There is also provided a drain case housing 15 and a float chamber drain pipe 16. A basket 17 of conventional character is revolvably mounted in the machine and a motor 18 is provided for motivating the same through a belt 19 and pulleys 20 and 21. A sprayer tube 23 extends horizontally into the machine between the chamber 14 and basket 17 and is connected to a cold water pipe 24.

In the embodiment of the invention illustrated in Figures 1 to 5, inclusive, there is provided a horizontally extending cylindrical air heater having an outer wall 25 and an inner wall 26 between which is provided a layer 27 of asbestos or other suitable insulation. An insulated conduit 28 provides a passage from without the heater for an electrical cord 29 connected with an electrical heating unit 30 mounted within the heater.

The heater is connected at its intake end with an exhaust nozzle 31 of an air impeller unit 32 having a carrying handle 33 affixed to the top thereof and having an electrical motor 34 operatively connected therewith and affixed thereto by bolts 35 which also serve to hold in position an arcuate-shaped bracket 36 having bolt-holes 37 for such purpose. The bracket is provided with a dependent shaft 37 which is slidably mounted in a vertically extending cylinder 38 mounted upon a base 39. At the upper end of the cylinder there is threaded a set screw which is adapted to come into contact with the shaft 37 and a retainer ring 41 is formed integrally with the upper end of the cylinder for the reception of the cord 29 and a cord 42 supplying electrical current to the motor 34.

The exhaust end of the heater is provided with a neck 42 upon which an adapter nozzle 43 is removably mounted, by means of latches 44 of

conventional character. The nozzle illustrated is provided with a forwardly extending arm 45 having a stopper 46 upon its outer end and is provided also with an upwardly extending outlet spout 47.

A thermostat housing 48 generally spherical in shape is provided and is adapted to be placed within the soap door 12 in the funnel 13 and is electrically connected with the heater 30 by an electrical cord 49. The thermostat is of conventional character and is not shown in detail and may, if desired, incorporate a timing device. Means may also, if desired, be provided for automatically opening the circuit to the heater unit 30 when the basket 17 ceases to revolve for any reason.

In the operation of this form of the invention, an adaptor nozzle 43 is placed upon the neck 42, such nozzle being selected for the particular type of washing machine with which the apparatus is to be used. In the one illustrated herein, the nozzle is moved into the drain case housing 15 and the stopper 46 will engage in the end of the pipe 16 to plug the same. The outlet spout 47 will enter and protrude a short distance into the chamber 14 so as to be above any water which might collect at the bottom of the chamber. The thermostat housing 48 is placed in the funnel 13 within the soap door 12. A switch 50 is provided with suitable circuits (not shown) and has provision for supplying current to the motor 18 while keeping water inlet valves idle. Air is then forced through the heater by the impeller 32 over the heating unit 30 to thereby heat the same and it is expelled from the spout 47 into the chamber 14 to dry clothes which may be placed therein, the thermostat acting as to cut the current to the heater when a certain temperature is attained within the washing machine. If steam or water vapor is produced by the action above described, cold water may be played along the inner sides of the chamber 14 to thereby condense the same whereby it may not escape into the room in which the apparatus is located. The heater, impeller and motor may be raised and lowered by adjusting the position of the shaft 37 in the cylinder 38 and then locking the same in position by the screw 40.

In the form of the invention shown in Figures 6 to 8, inclusive, there is shown a spin-dryer two tub type washing machine 51 having a grommet hole 52 in the cover 53 for the dryer section. The motor, impeller and heater are built in this case as a complete unit and there is provided a cylindrical outer housing 54 in the intake end of which is mounted a motor 55 having a shaft 56 to which is affixed impeller blades 57. An air intake manifold 58 is affixed to this end of

the housing 54. Within the central portion of the housing 54 there is provided an inner cylindrical liner 59 to which is affixed an electrical heating element 60 and suitable insulation 61 is packed between the outer housing 54 and the liner 59. A pair of longitudinally extending runners provide a support for the apparatus and a nozzle 63 having an upturned spout 64 is removably mounted on the exhaust end of the housing 54 and a flexible hose 65 is mounted on the spout 64 and connects with an outlet fitting 66 which is adapted to snugly fit in the grommet hole 52. A conduit 67 is provided for an electric cord 68 for supplying the heating unit 60 with electrical current.

In the operation of this form of the invention, clothes are placed in the basket 70 and the outlet fitting 66 is placed in the hole 52. The motor 55 will cause the impeller blades 57 to draw air into the manifold 58 and force the same over the heating unit 60 and thence through the nozzle 63 into the hose 65 and thence into the washing machine 51 where it will be forced against the clothes in the basket 70 to dry the same, it being understood that the basket will be caused to revolve during the drying procedure.

While but two forms of the invention have been shown and described herein, it will be readily apparent to those skilled in the art that many minor modifications may be made herein without departing from the spirit of the invention or the scope of the appended claim.

What is claimed is:

In a portable drying apparatus adapted to be used with a home laundry machine having a washing compartment and a drain case housing communicating therewith, the provision of an exhaust nozzle for an air heating apparatus, a horizontally extending arm affixed to the nozzle and a stopper affixed to the outer end of said arm, said nozzle adapted to extend through the drain case and into the washing compartment and said stopper being adapted to engage in a drain pipe conventionally associated with said drain case.
